Specification for Design.

Patented Aug. 26, 1913.

Application filed September 16, 1912. Serial No. 720,685. Term of patent 7 years.

To all whom it may concern:

Be it known that I, WILLIAM C. MOHR, a citizen of the United States, residing at Pittsburgh, in the county of Allegheny and State of Pennsylvania, have invented a new, original, and ornamental Design for Ladies' Rubbers, of which the following is a specification, reference being had to the accompanying drawings, forming part thereof.

In the drawings Figure 1 is a side eleva-

tion of a lady's rubber showing the general outline thereof. Fig. 2 is a front elevation of the shoe.

I claim—

The ornamental design for a lady's rubber, as shown.
